(57) **CLAIM**

The ornamental design for a flooring sample display stand, as shown and described.

DESCRIPTION

FIG. 1 is a perspective view of a flooring sample display stand showing my new design;

FIG. 2 is a front elevation view thereof, a rear elevation view being identical thereto;

FIG. 3 is a top plan view thereof;

FIG. 4 is a left side elevation view thereof;

FIG. 5 is a right side elevation view thereof;

FIG. 6 is a perspective view of a second embodiment of the flooring sample display stand;

FIG. 7 is a front elevation thereof, a rear elevation view being identical thereto;

FIG. 8 is a top plan view thereof;

FIG. 9 is a left side elevation view thereof; and,

FIG. 10 is a right side elevation view thereof.

In the drawings, the broken lines depict unclaimed subject matter only and form no part of the claimed design.

1 Claim, 6 Drawing Sheets
